Primary Examiner — Mimosa De(74) *Attorney, Agent, or Firm* — Shook, Hardy & Bacon L.L.P.(57) **CLAIM**

The ornamental design for a chest and base toolbox combination, as shown and described.

DESCRIPTION

FIG. 1 is a front perspective view of a chest and base toolbox combination of the present invention;

FIG. 2 is a top plan view thereof;

FIG. 3 is a front elevation view thereof; and,

FIG. 4 is a right side elevation view thereof with a left side elevation view being a mirror image.

A rear elevation view and a bottom plan view have been omitted as they do not form a portion of the claimed design. The broken lines shown in the drawings are directed to environment, are for informational purposes only, and form no part of the claimed design.
